US00D937566S

(12) **United States Design Patent** (10) Patent No.: **US D937,566 S**
(45) Date of Patent: **** Dec. 7, 2021**

(54) **KEY RING**

(71) Applicant: **HERMES SELLIER (Société par actions simplifiée)**, Paris (FR)

(72) Inventor: **Pierre-Alexis Dumas**, Paris (FR)

(**) Term: **15 Years**

(21) Appl. No.: **35/509,819**

(22) Filed: **Jan. 17, 2020**

(80) **Hague Agreement Data**

Int. Filing Date: **Jan. 17, 2020**

Int. Reg. No.: **DM/208093**

Int. Reg. Date: **Jan. 17, 2020**

Int. Reg. Pub. Date: **Jul. 17, 2020**

(51) **LOC (13) Cl. 03-01**

(52) **U.S. Cl.**

USPC **D3/207; D3/215**

(58) **Field of Classification Search**

USPC **D3/207-215**

CPC **A45C 11/32; A47G 29/10**

See application file for complete search history.
